CARRIER HANDLE FOR GARMENT HANGERS

Charles C. Cleland, Austin, Tex., assignor to Herald Corporation, Austin, Tex., a corporation of Texas

Filed Sept. 3, 1968, Ser. No. 13,361

Term of patent 14 years

Int. Cl. D8—03

U.S. Cl. D8—154

FIG. 1

FIG. 3

FIG. 4

FIG. 5

FIG. 2

FIG. 1 is a side elevational view of a carrier handle for garment hangers showing my new design;

FIG. 2 is an end elevation thereof, the end opposite being identical thereto;

FIG. 3 is a top plan view thereof;

FIG. 4 is a bottom plan view thereof; and

FIG. 5 is a perspective view thereof, the broken line showing of a hand and garment hanger hook being for illustrative purposes only.

I claim:

The ornamental design for a carrier handle for garment hangers, as shown and described.
